UNITED STATES PATENT OFFICE.

FRANK J. GROMMES, OF AURORA, ILLINOIS.

FOUNTAIN PEN.

Application filed June 19, 1924. Serial No. 721,058.

To all whom it may concern:

Be it known that I, FRANK J. GROMMES, a citizen of the United States, residing at Aurora, in the county of Kane and State of Illinois, have invented new and useful Improvements in Fountain Pens, of which the following is a specification.

This invention relates to fountain pens and more particularly to the filling means therefore.

An important object of this invention is to provide a fountain pen of the plunger type having simple means whereby the plunger may be drawn rearwardly for filling the body or chamber of the pen.

A further object is to provide a fountain pen wherein the parts are held in a compact position during the use of the pen.

A further object is to provide a fountain pen of the character specified which is of highly simplified construction, durable in use and is cheap to manufacture.

Other objects and advantages will be apparent during the course of the following description.

In the accompanying drawing forming a part of this application and in which like numerals are employed to designate like parts throughout the same,

Figure 1 is a perspective of the improved fountain pen;

Fig. 2 is a longitudinal sectional view through the same, the plunger being in its rearmost position or in that position which it occupies after the filling of the pen;

Fig. 3 is a longitudinal sectional view through the fountain pen with the plunger in its advanced position to draw a quantity of ink into the pen;

Fig. 4 is a horizontal sectional view taken on line 4—4 of Fig. 2.

In the drawing wherein for the purpose of illustration is shown a preferred embodiment of the invention, the numeral 5 designates the body or cylinder of a fountain pen, the said cylinder being provided at its forward end with a head 6 to which a nib 7 is connected in any suitable manner. A closure member 8 may be applied to the forward portion of the fountain pen to extend over the nib and if found desirable may be provided with a clip 9 by means of which the pen may be attached to one's pocket.

The cylinder 5 is provided with a chamber 10 within which a piston 11 is mounted

and it is believed to be obvious that when the piston 11 is drawn rearwardly and the forward portion of the pen is submerged in a bottle of ink a quantity of ink will be drawn into the chamber in advance of the piston. Particular attention is directed to the fact that the piston is provided with a packing 12 of suitable material and which allows the piston to move longitudinally when manually operated but has sufficient frictional contact with the wall of the chamber to prevent the same from rotating. Fig. 2 illustrates that the piston 11 has a bore 14 threaded for its entire length for engagement by the slightly enlarged threaded forward end 15 of a piston rod 16.

The piston rod 16 is securely connected by screw threads or otherwise with a cap 18 having its forward portion provided with an annular flange 19 adapted for threaded engagement with the reduced rear end 20 of the cylinder 5. Figs. 2 and 3 plainly illustrate that a gasket or washer 22 is positioned within the flange 19 and is adapted to bear against the reduced rear end 20 so as to prevent ink from escaping from the rear end of the cylinder.

In use when it is desired to fill the pen the rod 16 is threaded into the piston 11 and the piston is then advanced. The nib of the pen is now submerged in the ink and it is drawn rearwardly so a quantity of ink is drawn into the chamber 10. The rod 16 is now turned so that it is extended entirely through the piston 11. As previously stated the piston 11 will not turn when the rod 16 is turned as the frictional contact between the packing 12 and the wall of the chamber 10 prevents this. This permits the enlarged forward end 15 of the rod 16 to be disengaged from the piston 11 and the rod may now be moved forwardly to the position illustrated in Fig. 2 so that the pen will occupy but a small amount of space during the use of the same. It will be seen that when the parts are positioned as illustrated in Fig. 2 the cap 18 threaded on to the rear end of the cylinder 15 and the gasket 22 will positively prevent the leakage of ink.

Having thus described the invention, what is claimed is:

A fountain pen comprising a cylinder, having a chamber, the rear portion of the cylinder being provided with a reduced threaded portion, a piston arranged in said

cylinder and having a bore opening out through opposite ends of the piston and threaded for its entire length, a rod having an enlarged forward portion threaded in the bore of said piston and adapted to extend entirely through the piston and moved into the forward portion of the cylinder, a cap securely connected to said rod and adapted to be threaded on the rear terminal portion of said cylinder, said piston being

provided with a sealing medium frictionally contacting with the wall of the cylinder and holding the piston against turning and a packing carried by said cap and surrounding the rear portion of said rod whereby ¹⁵ leakage from said chamber is positively prevented.

In testimony whereof I affix my signature.

FRANK J. GROMMES.
